CRUSH-TYPE GRINDING WHEEL
TRUING DEVICELouis F. Polk, Dayton, Ohio, assignor to The
Sheffield Corporation, Dayton, Ohio, a corpora-
tion of Ohio

Application November 20, 1944, Serial No. 564,318

14 Claims. (Cl. 125—2)

1

This invention relates to grinding machines and more particularly to means for truing or surfacing the grinding wheel of such a machine.

One object of the invention is the provision, in a grinding machine, of a grinding wheel truing device including a rotatable crusher wheel which is carried for yielding movement on a support, together with provision for relatively moving the wheels into contact with one another, thus producing a yielding movement of the crusher wheel on its support followed by automatic locking of the crusher wheel against further yielding movement whereupon an automatic feeding movement of the wheels takes place.

Another object is the provision, in a grinding machine, of a grinding wheel truing device including a rotatable crusher wheel supported for yielding movement and so arranged that the wheels can be rapidly advanced into contact one with the other and produce yielding movement of the crusher wheel as a result of which a positive slow feeding movement of one of the wheels is initiated.

Another object is the provision of a grinding machine having a rotatable crusher wheel for forming the grinding wheel, the crusher wheel being actuated through a yielding connection to advance the crusher wheel into engagement with the grinding wheel until a yielding movement takes place between the crusher wheel holder and the actuator, this action being followed by an automatic adjustment of the wheels at a comparatively slow speed to force the wheels one into the other.

Another object is the provision of a grinding wheel of the character mentioned in which the crusher wheel holder is carried for yielding movement on an adjustable supporting slide which is positively controlled to cause rapid approach of the crusher wheel followed by a positive slow feed.

Another object is the provision of a grinding machine of the character mentioned in which the wheels are rotated at a speed substantially less than a normal grinding speed after they are brought into contact with one another and during the controlled positive feeding movement of one wheel into the other.

Other objects and advantages of the invention will be apparent from the following description, the appended claims, and the accompanying drawings, in which;

Fig. 1 is a top plan view of a crusher wheel mount embodying the present invention;

Fig. 2 is a vertical section on the line 2—2 of Fig. 1;

2

Fig. 3 is a vertical section on the line 3—3 of Fig. 2;

Fig. 4 is a front elevation of the crusher wheel mount;

Fig. 5 is a perspective view illustrating the adaptation of the invention to a grinding machine in which the work is carried on centers;

Fig. 6 illustrates the drive for the grinding wheel;

10 Figs. 7 and 8 are diagrammatic views respectively illustrating the electrical connections for the various operating elements, and the switch timing of the electric timing motor.

Referring more particularly to the drawings in which like parts are designated by the same numerals in the several views, 10 designates a grinding wheel of a grinding machine, the peripheral surface of which is adapted to be trued or surfaced by a rotatable crusher wheel 11, when

15 the two wheels are pressed in surface contact and rotated at a comparatively slow speed preferably of the order of 300 feet per minute. Either the crusher wheel or the grinding wheel may be positively rotated during the crushing action

20 although in the particular form of the invention illustrated for exemplary purposes it is the grinding wheel which is positively driven by an operating motor 12. The crusher wheel is carried for free rotation on its own axis and is operated at

25 substantially the same peripheral speed as the grinding wheel during the crushing operation through contact with the grinding wheel. A main driving motor 13 operates the grinding wheel rapidly at grinding speed during the actual grinding

30 of the work. It will be understood that the surface formation of the crusher wheel has a contour which is complementary to the form that is to be given to the grinding wheel, and as the two wheels are rotated the grinding wheel is

35 crushed away bit by bit until it assumes the desired shape. In the particular form of the invention illustrated the crusher wheel is provided with a series of similar annular ribs to provide ribs on the grinding wheel that may be used for grinding

40 screw threads on the workpieces during the rotation of the workpieces. If the workpieces are reciprocated back and forth in the plane of the grinding wheel, as in a surface grinder having a reciprocal work carrying table, the workpiece is

45 formed by the grinding wheel to provide a surface contour similar to that on the grinding wheel.

50 In accordance with the present invention, there is provision for advancing the crusher wheel and the grinding wheel into contact with one another at a comparatively rapid rate so that the wheel

may be brought into engagement without loss of time even though the extent of travel may be considerable as in case of a well-worn grinding wheel. This movement preferably takes place automatically, and after the wheels come into contact there is a yielding action in the moving means as a result of which there is a locking action against continued yielding movement, and a positive slow feed at a controlled rate so that the grinding wheel and the crusher wheel will be forced slowly into one another at a speed that does not create a breaking pressure destructive of the grinding wheel. In the form of the invention illustrated it is the crusher wheel that is moved first rapidly and then at a comparatively slow feeding rate, the crusher wheel mount being supported on the grinding wheel carriage or support. That support is guided for movement on the machine base in a direction towards and from the work.

As shown more particularly in Fig. 2, the crusher wheel 11 is rotatably supported on a carrying shaft 14 arranged in a bracket 15 having a readily movable end plate 16 which permits convenient assemblage of the parts. The bracket 15 is secured by fastening bolts 17 on a holder 18 which is slidably guided on a holder support 20 arranged on a housing 19 for movement of the crusher wheel toward and from the grinding wheel. The direction of movement of the crusher may coincide with a line radial of the grinding wheel or may be along a line parallel to and displaced from such a radius.

The holder 18 is grooved at 21 to receive one-half of the holder support 20 which consists of a two-piece slide having plate portions 23 fixed together. One of these plate portions is in sliding engagement with the holder 18 and the other is slidably guided in a groove 24 in the housing 19.

Fixed to the holder support 20 is an internally threaded boss 27 which is operable along a threaded adjusting shaft 28. The latter is suitably mounted for rotation in a bearing 29 at its upper end and a bearing 30 at its lower end, the upper end of the shaft projecting up through the cover plate 31 and having a square operating end 32 by means of which it can be manually turned. Rotational movement of the shaft 28 thus causes up or down travel of the support 20 (see Fig. 2), and if at that time this slide is fixed to the holder 18 a corresponding movement of the holder 18 will take place on the housing 19. However, at times, the parts 18 and 20 are not fixed together, and yielding movement of the holder 18 can take place on the support 20. A spring 34 interposed between a projection 35 at the lower end of holder 18 and the lower end of the slide or support 20 normally acts to yieldingly maintain the holder 18 in a lowered position with respect to the support 20.

The supporting slide 20 is provided with a horizontal groove 36 receiving a pin 37 on the end of a lever 38 which is arranged in a recess in the support 20 and is pivoted on the holder 18 by a short shaft 39. The axis of the shaft 39 is horizontally displaced from the pin 37 as will be apparent from Fig. 4 which indicates the normal position of the holder 18 with the crusher wheel out of contact with the grinding wheel and the spring 34 yieldingly keeping the holder 18 in a lowered position. When the support 20 is lowered by operation of the screw 28 until the crusher wheel contacts the grinding wheel and a resistance to further movement is imposed on the crusher wheel, the crusher wheel holder 18

remains stationary and the continued lowering of the support 20 compresses the spring 34. This relative motion of the holder 18 and support 20 causes the lever 38 to swing counterclockwise as viewed in Fig. 4 and as soon as it has turned a little distance, it moves away from and closes a limit switch 48 (see Fig. 4). The limit switch is so connected as to operate a solenoid 41 so that the solenoid plunger 42 travels upwardly and straightens a toggle linkage 43. This action moves a locking finger 44 into pressure contact with the lever 38, preventing further rotation of this lever and thus serving to lock or fix the holder 18 to the support 20. This secures the holder against further movement on the holder support 20 and then it will be apparent that continued rotation of the shaft 28 will cause positive movement of the crusher wheel toward the grinding wheel. It should also be noted that the movement of the crusher wheel toward the grinding wheel may take place through whatever spacing may exist between the two wheels until the crusher wheel engages the grinding wheel, the subsequent locking of the holder to the holder support then taking place automatically and affording firm engagement of the wheels under positive control.

After the wheels are brought into engagement with one another and as a result of the relative motion of the crusher holder on the crusher support, slow speed rotation of the grinding wheel is initiated. The wheels are brought into contact with one another while the grinding wheel is stationary and the main drive motor 13 is disconnected or de-energized. Excessive wear at localized points on the crusher wheel is thus prevented. After the crusher wheel contacts the grinding wheel, as previously mentioned, the operating motor 12 is energized and also the comparatively rapid rotation of the shaft 28 that takes place during rapid advance of the crusher wheel is automatically changed to a comparatively slow feeding rate, which continues through a predetermined interval of time or through a predetermined number of revolutions of the grinding wheel sufficient to give an adequate truing action on the grinding wheel. Further feeding movement of the crusher wheel is then automatically stopped during the continued rotation of the grinding wheel for two or three turns or so and while the holder 18 is secured to the holder support 20 and held in a fixed position so that a truly concentric form will be imparted to the grinding wheel. There is then an automatic reversal in the direction of the operation of the shaft 28 to produce a rapid withdrawal of the crusher wheel, and during at least the first part of this withdrawal the crusher wheel holder 18 is secured by the locking finger 44 to the support 20. This retracting movement of the shaft 28 continues until the holder 18 returns to its normal raised position shown in Fig. 2 and then the aligned arm arrangement of the toggle linkage 43 is broken by a controlling pin 46 which is brought up into engagement with the stop bar 47 fixed on the housing 19, the solenoid 41 being deenergized at this time. The finger 44 is thus withdrawn and the holder 18 is released from the support 20 so that the spring 34 again becomes effective to yieldingly support the holder. When the wheels are brought into engagement and before the crushing action actually starts a flow of coolant fluid is started by control of the automatic valve 82 in the coolant supply pipe 83 which leads to the housing 19. This flow is cut

off automatically after the crushing action is completed.

Referring again to Fig. 2, it will be noted that the housing 19 carries a variable speed adjusting motor 49 having a geared connection through the gears 50 and 51 to a gear 52 fixed to a clutch plate 53 which is free on the shaft 28. A clutch hub 54 splined or keyed to the shaft 28 may be operated into engagement with the clutch plate 53 to provide an operating connection between the shaft 28 and the motor 49 to turn the shaft 28 comparatively rapidly in one direction or the other, depending upon the direction of rotation of the motor. Gear 51 is arranged on a shaft 55 provided with a worm 56 meshing with the worm wheel 57 on shaft 58. Fixed on the shaft 58 is a worm 59 engaging worm wheel 60 which is free on the lower end of shaft 28. The worm wheel 60 is provided with a clutch plate 61 which may be engaged by the clutch hub 54 when the latter is lowered. The transmission mechanism just described operates the shaft 28 at a comparatively low rate of speed to lower the support 20 and thus slowly lower the crusher wheel into the grinding wheel during the truing action that takes place with these wheels rotating slowly in firm contact with one another. In this operation the speed of the motor 49 is adjusted in accordance with the grinding wheel size and construction to prevent excessive pressure between the crusher and the grinding wheel.

The clutch hub 54 is controlled automatically as by means of a control arm 62 having a lifting roller 63 engaging an operating cam 64. A lowering roller 65 is also provided on the arm 62, engaging a complementary lowering cam 66 (see Fig. 3). The cam 64 is provided with suitable recesses and camming surfaces to operate the clutch hub into engagement with the clutch plate 53 or 61 or to a position between those plates. The cam 64 is fixed to a ratchet wheel 67 controlled by a ratchet pawl 68 on a lever 69 which is operated by solenoid 70. The latter is controlled automatically at the proper time in the sequence of operation as will be presently described.

Before bringing the crusher wheel into engagement with the grinding wheel, the upper portion of the grinding wheel cover 71 is moved out of the path of the crusher wheel. As shown in Fig. 4, the cover housing 11 is provided with two slidable cover sections 72 and 73 which are movable laterally away from one another and away from a location below the crusher wheel. Thus the cover section 72 may be moved to the left as viewed in Fig. 4 into the dotted position, while the other cover section 73 is moved correspondingly to the right. This movement may be provided by a suitable linkage including link 74 pivotally mounted at 75 on the main portion of the grinding wheel housing. Arms 76 are connected to these links 74 and to an operating stud 77 which is slidably guided in a groove 78 in the grinding wheel housing. The stud 77 is provided on the armature 79 of solenoid 80 so that when the solenoid is energized the arms 76 will be raised and spread, moving the sections 72 and 73 outwardly. The solenoid 80 is energized automatically at the time of initiation of the crushing cycle. After the crusher wheel holder is raised to retracted position, the solenoid 80 is de-energized and the cover sections 72 and 73 are returned by spring 81. When the crushing cycle is completed the grinding wheel may be traversed

as required to properly engage the work and the grinding operation performed by operating the grinding wheel at normal grinding speed by the driving motor 13. An overrunning clutch 85 permits high speed operation of the grinding wheel without driving the operating motor 12.

An adjustment is provided for properly positioning the axis of the crusher wheel 11 with respect to the axis of the grinding wheel. For this purpose the bracket 15 is adjustably supported on the holder 18 for movement about a line tangent to the crusher wheel and midway between the ends of the crusher wheel where it engages the grinding wheel. The axes of the grinding wheel and the crusher wheel may thus be arranged in exact parallelism or slightly out of a true parallel condition to compensate for deflections that might take place in the shafts or bearings of either one of these wheels during the crushing operation. The bolt holes which receive the holding bolts 17 are arranged in the bracket 15 in a concentric arrangement with respect to this axis of adjustment just mentioned and the bolts 17 pass through arcuate slots provided in the wall portions 83 of the holder 18 where the holder extends down at the sides of the bracket 15.

Fig. 7 shows the various electrical connections of the apparatus. The motor 13 for driving the grinding wheel during the grinding operation at a suitable normal grinding speed is connected to a three-phase supply source 88 through a switch a. This supply source is also connected through switch b to the operating motor 12 which turns the grinding wheel at a reduced speed in the crushing operation, although it should be understood that a single motor can be used in place of the two motors 12 and 13 if suitable speed variation is provided. The reversible adjusting motor 49 is supplied either through a switch c or a switch d depending upon the direction of rotation desired. The switch e connects the source of power to the solenoid 80 which, when energized, moves the cover sections 72 and 73 out of the path of the crusher wheel. Switch b1 controls the energization of the solenoid 41 which governs the locking of the crusher holder to the crusher supporting slide 20. Switch f connects to the solenoid 70 which governs the clutch operating mechanism. Another switch c1 controls the solenoid valve 82 which governs the flow of coolant fluid in the crushing operation.

One phase of the supply line is connected across the primary of a transformer 89 having a secondary which is connected to the lead lines 90 and 91. The dead line 91 is connected to one side of switch controlling relays A, B, C, D, E and F, which respectively control the operation of the switches a, b, c, d, e and f. The lead line 90 connects through a start switch 92 which is normally open, a normally closed stop switch 93, normally closed relay control switch e1 to the motor controlling relay winding A so that when the start switch 92 is closed, the grinding wheel motor 13 will be energized during the grinding operation. The relay coil A closes a switch a1 to complete a holding circuit about the start switch 92.

The lead line 90 is connected to the switch controlling relay E by a start switch 94 and a normally closed stop switch 95. Although the operator would normally stop the main grinding wheel motor 13 by operating the stop switch 93 before starting a crushing cycle of operations,

the deenergization of the motor 12 is insured by the switch e_1 which is opened when the relay E is energized. The energization of the relay E closes the switch e to retract the wheel guard cover sections. When the relay E is energized, it also closes a holding circuit switch e_2 which is connected through normally closed limit switch 96 around the start switch 94. This limit switch 96 is momentarily opened by the toggle links 43 as the toggle links move from their straightened position to the angular position shown. As the limit switch 96 is closed except when the toggle links move to an angular position at the end of a crushing cycle, the holding circuit will be maintained around the start switch 94 until the crusher holder has been moved up to a raised position, elevating the crusher above the wheel guard position. The opening of the switch 96 at that time will automatically interrupt the current flow to the relay winding E at the end of a crushing cycle.

When the relay winding E is energized, it closes another switch e_3 which is connected through a microswitch 98 which is normally closed, a normally closed switch d_1 (which is opened when the relay coil D is energized), and a cam controlled switch 99 to the relay winding C. The microswitch 98 is provided as a safety factor and is only opened in case of excessive movements of the lever 38 in a counterclockwise direction as viewed in Fig. 4. The automatically controlled switch 99 is closed and the cam 100 which controls it is stationary at the time. This cam is provided on a cam shaft which constitutes a timing mechanism, the cam shaft being driven by a small timing motor 101 which, when energized, operates the cam shaft through one revolution in a predetermined time interval and then stops. Fig. 8 shows the timing of the switches operated by the various cams on the shaft of this motor 101. The energization of the relay C closes the switch c so that the adjusting motor 49 will start operating and rapidly move the crusher holder downwardly since the clutch controlling arm 62 will be raised at the time, holding the clutch hub 54 in engagement with the upper clutch disc 53 as diagrammatically shown in this figure. When the relay coil C is energized it also closes the switch c_1 to start the coolant flow to the crusher so that coolant is supplied to the grinding wheel all during the down movement of the crusher.

The downward movement of the crusher holder will continue at a comparatively rapid rate until the crusher engages the grinding wheel and the yielding action takes place between the holder 18 and the plate portion 23. As one portion of lever 38 is connected to the holder 18 and another portion operates in the horizontal groove in plate 23, see Figs. 2 and 4, the lever 38 swings counterclockwise and permits closure of the limit switch 40 which is normally held open by the lever 38. As soon as the switch 40 closes it completes a circuit through a switch d_2 , through a cam operated switch 103 closed at this time, to the relay coil F, which then immediately closes switch f energizing solenoid 70 and moving the ratchet wheel 67 to turn the cam 64 through one step which serves to lower the arm 62, disengaging clutch face 53 and engaging the lower clutch face 61 so that the shaft 28 will continue its rotation in the same direction but at a greatly reduced speed. The lowering of the clutch disc closes a limit switch 104 as soon as full engagement takes place with the lower clutch face 61. The clutch hub 54 is carried for yielding move-

ment on the arm 62 by means of springs 62' interposed between lugs on that arm and slide members 54' that carries the clutch hub so that the two clutch parts may properly position themselves with the teeth of one opposite the spaces on the other. When the switch 104 closes a connection is made through lead line 105 to the motor 101, starting this motor and causing the rotation of the shaft that operates the cams 106 controlling switch 103, cam 100 controlling switch 99, two additional cams 107 and 108 controlling switches 109 and 110 respectively, and a cam 113 which closes a holding circuit through a switch 114 by means of which the motor 101 is stopped after one revolution of the cam shaft. At the same time the microswitch 104 is closed, that is, after the crusher has engaged the grinding wheel and the arm 38 closes switch 40 as previously mentioned, switch 104 being closed at the time, a circuit is completed through the relay coil B through the cam operated switch 109 closed at this time. The energization of the relay coil B closes a holding switch b_2 around the microswitch 104. It also closes switch b to start the grinding wheel operating motor 12 to drive the grinding wheel at crushing speed. At the same time the energization of relay coil B also closes switch b_1 to energize the solenoid 41 and lock the crusher holder to its supporting slide.

After a predetermined time interval dependent upon the amount of time required for a crushing operation and preset in accordance with the particular grinding wheel characteristics, switch 99 will be automatically opened, deenergizing the relay C and thus causing the switch c to open so that the motor 49 will be deenergized. The downward movement of the crusher is thus stopped although the operating motor 12 continues to rotate and any eccentricities in the surface of the grinding wheel are removed during a few revolutions of the grinding wheel. At the time switch 99 opens, the cam controlled switch 103 is closed again to energize solenoid 70 and move the ratchet controlled cam plate 64 through another step in which the clutch hub 54 is moved to a neutral position. After a short time interval sufficient for a few revolutions of the grinding wheel without further feed of the crusher the cam 107 opens switch 109, deenergizing relay B to open the switch supplying the motor 12, and also open the switch b_1 and deenergize the solenoid 41 so that the lock between the crusher holder and its supporting slide can be subsequently released when the crusher holder is fully retracted. After the deenergization of the motor 12 another energization of the solenoid 70 takes place through the cam controlled switch 103, moving the clutch hub up into engagement with the clutch face 53 so that the shaft 28 will be rapidly rotated in a direction to raise the crusher holder after the motor 49 is energized. The motor 49 is now energized by the cam controlled switch 110, energizing the relay D. Energization of the relay coil D also closes the normally open switch d_3 providing a holding circuit so that the up travel of the crusher holder continues until the switch e_3 opens. Switch e_3 is opened by the deenergization of the relay coil E when the limit switch 96 is temporarily open circuited by the movement of the toggle arms into an angular position when the crusher holder is fully retracted. As soon as the relay coil E is deenergized, the various circuits are interrupted and the parts are then again in the starting position ready for another cycle.

When the relay coil D was last energized it opened a switch d2 interrupting further current supply to the solenoid controlling coil F preventing further indexing operation of the ratchet plate until the next cycle. Shortly after the switch 110 closed to start the up feed drive of the motor 49, a full revolution of the cam shaft is completed and switch 114 automatically broken to stop further operation of motor 101. At the time of deenergization of the relay coil E at the end of the crushing cycle, the switch e is opened again, deenergizing the solenoid 80 and causing the return of the cover guard sections of the grinding wheel housing. At the time the relay coil C was deenergized, at the end of the down feed movement, the switch c1 which it controls is opened and the coolant supply to the crusher is stopped.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A grinding machine having a rotatable grinding wheel, a grinding wheel support, a rotatable crusher wheel for forming the grinding wheel, a crusher wheel holder rotatably supporting said crusher wheel, a power operated actuator having a yielding connection to said holder, means for moving said actuator to advance said crusher wheel into engagement with said grinding wheel and then cause relative yielding action between the holder and the actuator, means automatically operable as a result of such yielding movement for locking the holder to the actuator, and means for automatically adjusting one of said wheels positively at comparatively slow speed after said locking action to force said wheels one into the other.

2. A grinding machine having a rotatable grinding wheel, a grinding wheel support, a rotatable crusher wheel for forming the grinding wheel, a crusher wheel holder rotatably supporting said crusher wheel, a power operated actuator slidably supported on said grinding wheel support and slidably supporting said crusher wheel holder, said actuator having a yielding connection to said holder normally maintaining said holder in a predetermined position, means for moving said actuator to advance said crusher wheel into engagement with said grinding wheel and then cause relative yielding action between the holder and the actuator, means automatically operable as a result of such yielding movement for locking the holder to the actuator, and means for automatically adjusting one of said wheels positively after said locking action to force said wheels one into the other.

3. A grinding machine having a rotatable grinding wheel, a grinding wheel support, a rotatable crusher wheel for forming the grinding wheel, a crusher wheel holder rotatably supporting said crusher wheel, a power operated actuator having a yielding connection to said holder, means for moving said actuator to advance said crusher wheel into engagement with said grinding wheel and then cause relative yielding action between the holder and the actuator, power means for driving one of said wheels at a peripheral speed less than the normal grinding speed of the grinding wheel, means automatically operable as a result of such yielding movement for lock-

ing the holder to the actuator and initiating operation of said power means, and means for automatically adjusting one of said wheels positively at comparatively slow speed after said locking action to force said wheels one into the other.

4. A grinding machine having a rotatable grinding wheel, a grinding wheel support, a rotatable crusher wheel for forming the grinding wheel, a crusher wheel holder rotatably supporting said crusher wheel, guard means between said wheels, a power operated actuator having a yielding connection to said holder, means for removing said guard means and for moving said actuator to advance said crusher wheel into engagement with said grinding wheel and then cause relative yielding action between the holder and the actuator, means automatically operable as a result of such yielding movement for locking the holder to the actuator, and means for automatically adjusting one of said wheels positively at comparatively slow speed after said locking action to force said wheels one into the other.

5. A grinding machine having a rotatable grinding wheel, a grinding wheel support, a rotatable crusher wheel for forming the grinding wheel, a crusher wheel holder rotatably supporting said crusher wheel, a power operated actuator slidably supported on said grinding wheel support and slidably supporting said crusher wheel holder, said actuator having a yielding connection to said holder normally maintaining said holder in a predetermined position, means for moving said actuator to advance said crusher wheel into engagement with said grinding wheel and then cause relative yielding action between the holder and the actuator, power means for driving one of said wheels at a peripheral speed less than the normal grinding speed of the grinding wheel, means automatically operable as a result of such yielding movement for locking the holder to the actuator and initiating operation of said power means, and means for automatically adjusting one of said wheels positively at a comparatively slow speed after said locking action to force said wheels one into the other.

6. A grinding machine having a rotatable grinding wheel, a grinding wheel support, a rotatable crusher wheel for forming the grinding wheel, a crusher wheel holder rotatably supporting said crusher wheel, a holder support on which said holder is mounted for yielding movement in a direction towards and from the grinding wheel, means for moving one of said supports to cause engagement of said wheels and yielding movement of said holder on the holder support, means for automatically locking said holder to the holder support subsequent to engagement of said wheels, and means for automatically moving said holder support at comparatively slow speed to cause further approach of the pressure wheel and the grinding wheel axes.

7. A grinding machine having a rotatable grinding wheel, a grinding wheel support, a rotatable crusher wheel for forming the grinding wheel, a crusher wheel holder rotatably supporting said crusher wheel, a holder support on which said holder is mounted for yielding movement in a direction towards and from the grinding wheel, power means for positively moving one of said supports at a substantially constant rate of advance to cause engagement of said wheels and yielding movement of said holder on the holder support, and means for automatically adjusting one of said supports at comparatively slow speed

with a substantially constant rate of advance to force said wheels one into the other.

8. A grinding machine having a rotatable grinding wheel, a grinding wheel support, a rotatable crusher wheel for forming the grinding wheel, a crusher wheel holder rotatably supporting said crusher wheel, a holder support on which said holder is mounted for yielding movement in a direction towards and from the grinding wheel, means for moving one of said supports to cause engagement of said wheels and yielding movement of said holder on the holder support, means for automatically locking said holder to the holder support subsequent to engagement of said wheels, and means for automatically adjusting one of said supports at comparatively slow speed after said holder is locked to the holder support to force said wheels one into the other.

9. A grinding machine having a rotatable grinding wheel, a grinding wheel support, a rotatable crusher wheel for forming the grinding wheel, a crusher wheel holder rotatably supporting said crusher wheel, a holder support on which said holder is mounted for yielding movement in a direction towards and from the grinding wheel, means for positively moving said holder support at a rapid rate to cause engagement of said wheels and yielding movement of said holder on the holder support, means for automatically locking said holder to the holder support subsequent to engagement of said wheels, and means for automatically adjusting said holder support at comparatively slow speed after said holder is locked to the holder support to force said wheels one into the other.

10. A grinding machine having a rotatable grinding wheel, a grinding wheel support, a rotatable crusher wheel for forming the grinding wheel, a crusher wheel bracket carrying said crusher wheel for rotation about its own axis, a holder for said bracket on which said bracket is adjustably mounted for adjustment of the angular relation of the axes of said wheels, a power operated actuator, means for moving said actuator to advance said crusher wheel at a substantially constant rate of advance into engagement with said grinding wheel, and means for automatically adjusting one of said wheels to force said wheels one into the other.

11. A grinding machine having a rotatable grinding wheel, a grinding wheel support, a rotatable crusher wheel for forming the grinding wheel, a crusher wheel bracket carrying said crusher wheel for rotation about its own axis, a holder for said bracket on which said bracket is adjustably mounted for adjustment of the angular relation of the axes of said wheels, a power operated actuator having a yielding connection to said holder, means for moving said actuator to advance said crusher wheel into engagement with said grinding wheel and then cause relative yielding action between the holder and the actuator, means for locking the holder to the actuator, and means for automatically adjusting one of said wheels positively at comparatively

slow speed to force said wheels one into the other.

12. A grinding machine having a rotatable grinding wheel, a grinding wheel support, a rotatable crusher wheel for forming the grinding wheel, power means for slowly rotating said grinding wheel, a crusher wheel holder rotatably supporting said crusher wheel, a holder support on which said holder is mounted for movement in a direction towards and from the grinding wheel, means for moving said holder support at a comparatively rapid rate to cause engagement of said wheels, means for automatically locking said holder to the holder support subsequent to engagement of said wheels and for initiating operation of said power means, and means for automatically adjusting one of said supports at comparatively slow speed after said holder is locked to the holder support to force said wheels one into the other.

13. A grinding machine having a rotatable grinding wheel, a grinding wheel support, a rotatable crusher wheel for forming the grinding wheel, a crusher wheel holder rotatably supporting said crusher wheel, a holder support on which said holder is mounted for yielding movement in a direction towards and from the grinding wheel, screw means for moving said holder support to cause engagement of said wheels and yielding movement of said holder on the holder support, means for automatically locking said holder to the holder support subsequent to engagement of said wheels, and means for automatically adjusting said screw means at comparatively slow speed after said holder is locked to the holder support to force said wheels one into the other.

14. A grinding machine having a rotatable grinding wheel, a grinding wheel support, a rotatable crusher wheel for forming the grinding wheel, a crusher wheel holder rotatably supporting said crusher wheel, a holder support on which said holder is mounted for movement in a direction towards and from the grinding wheel, power mechanism for moving said crusher wheel holder to move the crusher wheel towards and from the grinding wheel at a substantially constant rate of advance, power mechanism for automatically feeding one of said supports at a substantially constant rate of advance to cause relative approach of the axes of the grinding wheel and crusher wheel, and means automatically operative upon engagement of the crusher wheel with the grinding wheel to stop the operation of said first named power mechanism and start the operation of the second named power mechanism.
